DESIGN FOR A BATHROOM VANITY CHAIR

Eugene J. Lux, New York, N. Y., assignor to
Columbia Protekosit Company, Inc., Carl-
stadt, N. J., a corporation of New Jersey

Application September 14, 1946, Serial No. 133,332

Term of patent 7 years

(Cl. D15—8)

To all whom it may concern:

Be it known that I, Eugene J. Lux, a citizen of the United States and resident of New York city, in the county of New York and State of New York, have invented a new, original, and ornamental Design for a Bathroom Vanity Chair, of which the following is a specification, reference being had to the accompanying drawing, forming a part thereof, and of which Fig. 1 is a perspective view of a bathroom vanity chair showing my new design; Fig. 2 is an enlarged view in front elevation thereof; Fig. 3 is a view in side elevation of the same; and Fig. 4 is a sectional view taken on the line 4—4 of Fig. 3.

I claim:

The ornamental design for a bathroom vanity chair, substantially as shown.

EUGENE J. LUX.
